MACHINE FOR FEEDING AND CUTTING
LABELSJacob Hochman and Simon R. Wakoff, Brooklyn,
N. Y., assignors to B & J Machine Co. Inc., a
corporation of New York

Application November 2, 1939, Serial No. 302,574

1 Claim. (Cl. 270—93)

The invention relates to improvements in apparatus particularly adapted for the cutting, folding and counting of fabric labels and the like, of the type and nature as employed in marking tags, labels and similar designating indicia for garments and other forms of articles of manufacture.

The object of the invention lies in the providing of means arranged to receive a spool of label tape consisting of a continuity of printed fabric labels, one end of which is threaded through mechanism for cutting or severing the individual labels therefrom, means for feeding said labels through folding and creasing structure, passing said labels through hot-press creasing and ironing rollers, and of feeding said labels through tabulating mechanism for counting the same either individually or in predetermined group lots as desired.

In the following there is described the major essentials of the invention, the features thereof being more clearly defined hereinafter in the claim forming part hereof.

In the drawings Fig. 1 is an end elevation of the label feeding, cutting, folding and tabulating apparatus; Fig. 2 is a plan elevation of the device; Fig. 3 is a horizontal sectional view of the apparatus taken on the line 3—3 of Fig. 2 of the drawings; Fig. 4 is an elevation partly in sectional view of the cutting mechanism, and means for actuating the same; Fig. 5 is a plan elevation of the folding-creasing device forming part thereof; Fig. 6 is a cross sectional view of the folding forming head taken on the line 6—6 of Fig. 5, and Fig. 7 is a perspective in elevation of a severed label after folding.

Similar numerals of reference indicate similar parts throughout the several views of the drawings. In the drawings 1 indicates a supporting frame carrying a motor 2, a pulley 3 and belting 4 for transmitting power to a main sheave 5 disposed on shaft 6 mounted in suitable bearings therefore on secondary or auxiliary supporting frame 7. Table top 8 of frame 1 has mounted thereon goose-neck arm 9 provided with apertured bearing 10 to receive the pin of sheave 11 carrying a spool of label tape 12 the free end of which is threaded into the feeding, cutting, folding and tabulating mechanism hereinabove described.

Auxiliary frame 7 consists of a table 13 mounted on member 8 of frame 1, carrying thereon standard brackets 14 supporting at their upper fulcrumed heads 15 supporting bearings 16, and at the lateral end of shaft 6, a standard 17 pro-

vided with a fulcrum head 18 supporting bearing 19 and at the opposite end bearing 20 for said main operating shaft 6, the latter being actuatable through sheave 5 of the belt driven power transmission.

Shaft 6 has mounted thereon a cam 21 for actuating the strip or tape feeding mechanism, a cam 22 for actuating the knife or cutter mechanism, a cam 23 for lifting the belt feeding means and a worm gear 24 for actuating the folded label pressing mechanism. Table 13 of the auxiliary frame 7 has mounted thereon a standard support 25 having disposed thereon a stationary platform 26 upon which the severed labels are deposited after cutting and from which the belt feeding mechanism carries it to the forming folding mechanism.

Platform 13 has mounted thereon vertical supporting brackets 27 carrying arms 28 into which the movable belt feeding means is disposed which consists of laterally extending side frames 29 pinioned therein at 30 supported at their central position by tie rod 31 and having mounted in bearings 32 a pulley 33 and at their opposite ends a shaft 34 carrying a drum 35, said pulley 33 and drum 35 having mounted thereon a feed belt 36, the ends of said shaft 34 finding bearing in the loose socket ends 37 of standards 38, the latter thereof carrying vertically extending rocker supports 39 the upper angular ends of which have mounted therein plungers 40 having at their lower ends loose bearing caps 41 controlled by means of compression springs 42 for maintaining the bearing pressure on said shaft 34 the object of which is to provide means for displacing or moving said feeding mechanism away from the adjacent operative parts of the apparatus for observation purposes, said tie-rod 31 having disposed therein a belt tensioning roller 44 and one member or side frame 29 may likewise have mounted therein a similar tensioning roller 45 for maintaining the equalized travel of the belt 36 for feeding the several labels through the formative folding and enumerating portions of the structure.

Table 13 has attached thereto a transverse and upwardly extending frame 46 carrying a supporting plate 47 having pivotally mounted therein at 48 a rocker arm 49 carrying at its upper end a sliding block 50 which is in turn slideably disposed on guide rods 51 set in one leg of frame 27 and one upright of frame 46. Said block 50 has mounted therein a yoke 52 carrying a pin 53 carrying an adjustable spanner 54 into which the feeding leg 55 is mounted and set on a diag-

onal plane to assist in its step-like operation of feeding the label tape 12 from its supply spool 11. Said block 50 is provided with pressure set screws 56 for maintaining its sliding action on rods 51 and has attached thereto a cable 57 passing over pulley 58 on frame 46 and carrying on its end a weight 59 for assisting the feeding mechanism in its return positions. Rocker arm 49 has cut therein a slot 60 to receive pin 61 on actuating arm 62 mounted on stud 63 which is disposed eccentrically on cam 21 to produce a cam actuator means, said cam 21 being mounted on the main drive shaft 6 of the structure as previously defined hereinabove.

Frame 46 has mounted thereon an auxiliary support 64 carrying a reception plate 65 having mounted on its outer end a label tape tensioning bar 66 under which said tape passes, said plate 65 having adjustably mounted thereon transversely with relation thereto guide plates 67 spaceable toward and away from one another to provide means for taking label tapes of varying widths, the space between said plates 67 being the feeding area in which the feeding leg 55 protrudes said label tape to the cutting unit of the device.

Cutter table 26 is mounted on frame 68 which has pivotally mounted therein at 69 a knife blade 70 mounted on arm 71 having a slot 72 engaging pin 73 on reciprocable stem 74 mounted in bearing 75 and having mounted in its lower end a roller 76 engaging the actuator cam 22 on said shaft 6, the operation thereof being by reason of the vertically disposed moment of said stem 74 by said cam 22 the knife blade 70 receives its oscillatory action to effect its cutting action.

Feeding belt 36 has disposed against it on its under side tensioning rolls 77 for maintaining a pressure thereon when slide 78 mounted in guides 79 are actuated by arm 80 to place a lifting moment against belt 36 to permit the single severed label to be carried thereby to the former matrix 81 said arm 80 being actuated by the lifting moment provided by said cam 23 on said shaft 6. Each vertical action of stem 74 trips a finger 82 on tabulator 83 provided for counting the number of severed or cut labels passing through the apparatus. The forming matrix 81 consists of a supporting plate 84 disposed on straps 85 attached to side plates 29 and comprises a converging side walled chute 86 having curved forming rims 87 and a crimping plate 88 arranged to fold the ends of the label over on itself and through

which the belt 36 passes to engage the said labels by friction to convey same to the pressing drum 35 wherewith an electrically heated ironing roll 89 is disposed on journals, a gear 90 on shaft 34 meshing with gear 91 on said heat roller receiving its transmitted power through worm gear 92 engaging worm 24 on the main drive shaft 6 of the apparatus. After the labels are hot pressed between drum 34 and heated ironer 89, a discharge chute 93 mounted at the discharge end of the machine receives such completely cut formed counted and pressed labels 94 for final disposition. The operation of the apparatus is as follows: A spool of printed fabric labels in the form of an endless tape is mounted on the machine, one end threaded into the feeding mechanism whereby continuous actuation said label tape is fed to a continuous cutting mechanism whereat each cutting action the labels are counted and passed separately to a formative folding unit, wherein same have then severed ends folded over and are conveyed to hot press means between the rollers of which the label is completely ironed and flattened thence to a discharge collective means as desired.

It is obvious that the apparatus may be varied in many ways without departing from the spirit of the invention.

What we claim and desire to secure by Letters Patent of the United States is:

A device of the character described comprising a label cutting, counting, creasing and pressing mechanism consisting of main and auxiliary supporting means, a continuous roll of unformed tape disposed on a suitable supporting spindle forming part of said mechanism, feeding mechanism for said tape, means for segregating said tape into individual labels, means for counting said labels passing said cutting means, means for carrying said labels from said cutting means, means for creasing the edges of said labels in folded and crimped form, an electrically heated pressing means, means for carrying said folded labels through said crimping means to and through said pressing means, and means operative from the drive shaft of said actuating mechanism controlling the feeding, cutting, folding, counting and pressing means from one or a common point.

JACOB HOCHMAN.
